BATH TUB

Alfred H. Haberstump, Detroit, Mich., assignor to
 The Murray Corporation of America, Detroit,
 Mich., a corporation of Delaware

Application December 28, 1940, Serial No. 372,079

1 Claim. (Cl. 4—186)

My invention relates to bath tubs, and particularly to an open type of tub supported on legs which are permanently attached thereto.

The tub is stamped as a unit from a sheet of metal and provided with a rolled edge. The legs are stamped from a sheet of metal from a single die and shaped on the top to fit the contour of the lower corner of the tub. The top edge of the legs is flanged inwardly so that the legs may be permanently attached by welding. The legs are of V-shaped construction, with the inner faces open since these faces are invisible. The edges of the inner faces and the floor engaging portions are also flanged inwardly and are joined by an angle member to provide material strength.

Accordingly, the main objects of my invention are; to provide a set of legs for a bath tub which are formed in a single set of dies and further shaped at the top to conform to the contour of the tub; to form legs of V-shape construction having flanges at the open faces, the top portion of which is formed to the contour of the tub to which the top flanges are welded; to form a set of legs for a tub from sheet metal in a single set of dies, which legs are flanged at the bottom and at the inner open face, and shaped at the top to conform to the shape of the corner of the tub and flanged inwardly and welded thereto; and in general, to provide a set of legs for a tub which are of unique construction stamped from a single set of dies and which are permanently attached to the tub.

Other objects and features of novelty of my invention will be either specifically pointed out or will become apparent when referring, for a better understanding of my invention, to the following description taken in conjunction with the accompanying drawing, wherein:

Figure 1 is a plan view of a tub having legs thereon embodying features of my invention;

Fig. 2 is an enlarged sectional view of the structure illustrated in Fig. 1, taken on the line 2—2 thereof;

Fig. 3 is an enlarged sectional view of the structure illustrated in Fig. 1, taken on the line 3—3 thereof;

Fig. 4 is an enlarged sectional view of the structure illustrated in Fig. 1, taken on the line 4—4 thereof; and,

Fig. 5 is a sectional view of the structure illustrated in Fig. 4, taken on the line 5—5 thereof.

The tub 10 comprises a sheet of metal which has been formed into a tub body having a rolled rim 11 at the edge. Faucet openings 12 and a drain opening 13 are provided in the drain end

of the tub, while a sloping end portion 14 is provided in the bell end thereof.

A set of four legs 15 are welded to the bottom of the tub to form a unit construction therewith. 5 The set of legs are made from the same dies and are substantially of V-shape in section, as illustrated in Fig. 5. A front face 16 is arcuately extended at the sides, at 17, and flanged inwardly at the front, at 18. The bottoms of the sides 19 and the front face 16 are flanged inwardly at 19 and 21, respectively, to provide a supporting surface. The flanges 18 and 19 are joined to each other at adjacent and opposite corners by an angle shaped bracing element 22. A plurality of 10 indentations 23 are provided around the lower end of the legs for the purpose of ornamentation.

The front face 16 of the leg is curved inwardly toward the tub at the top which shape is followed by the flanges 18 at the inner edges of the 20 leg. All of the legs are constructed from the single set of dies and are therefore exactly the same. Additional forming tools are provided for the rear and the right and left front legs to shape the top thereof to conform to the shape of the 25 arcuate corner portion to which the legs are joined. After being so shaped the top edges are formed inwardly to provide a flange 24 by which the welding operation is performed between the tub and the leg.

30 In view of the slope to the tub, the top formation of each of the legs at the bell end of the tub is different so that a tool and fixtures must be provided to shape the tub contour and the flanges 24 on each of the front legs to conform to the 35 particular shape of the curved lower edge of the tub to which the leg is attached. The drain end of the tub is flat so that there is no difference between the right and left hand legs for the drain end. In view of the position of the inner face of the legs directly under the tub, this face is left open. The legs and outer surface of the tub is finished as a unit, either by porcelain enameling or by painting or spraying an enamel thereon. A base coating of porcelain enamel may be placed over the inner and outer surface and the inner 40 surface finished with porcelain enamel while the outer surface is finished by painting over the base coating of enamel.

The tub formed in this manner is of unit construction and the legs provide a sturdy appearance in view of the box section type of construction. Various means may be provided for ornamenting the legs other than the indentations 23 and other shapes besides the particular V-shape 45 herein illustrated may be employed. I, therefore,

do not wish to be limited to the particular contour shown as the novel invention embodies the formation of stamped legs from a single set of dies and permanently attaching the legs to the outer surface of the tub.

While I have described and illustrated but a single embodiment of my invention, it will be apparent to those skilled in the art that various changes, omissions, additions and substitutions may be made therein without departing from the spirit and scope of my invention, as set forth in the accompanying claim.

What I claim is:

In a bath tub, a tub proper made from a single sheet of metal having a rolled edge and faucet and drain openings, and a set of four legs for said tub each of which are V-shaped in transverse

5 cross section having flanges at the bottom and inner face and having a top flanged edge conforming to the contour of the tub at the point of engagement where they are welded to form a permanent unit construction.

ALFRED H. HABERSTUMP.
